IRRIGATION SOCK HOLDER

Elmer G. Heinrich, 824 E. 6th, Goodland, Kans. 67735

Filed Aug. 17, 1965, Ser. No. 86,606

Term of patent 14 years

(Cl. D91—3)

FIGURE 1 is a front elevational view of an irrigation sock holder, the sock and an irrigation pipe being shown in dashed lines, illustrating my new design;

FIG. 2 is a side side elevational view thereof;

FIG. 3 is a side elevational view illustrating the side thereof opposite from the side shown in FIG. 2;

FIG. 4 is a top plan view of the holder; and

FIG. 5 is a fragmentary cross-sectional view taken along line 5—5 of FIG. 3 of the irrigation sock holder.

The broken line disclosure is shown for illustrative purposes only.

I claim:

The ornamental design for an irrigation sock holder, as shown and described.
